UNITED STATES PATENT OFFICE

EDWARD J. BRANDT, OF WATERTOWN, WISCONSIN, ASSIGNOR TO BRANDT AUTOMATIC CASHIER COMPANY, OF WATERTOWN, WISCONSIN, A CORPORATION OF WISCONSIN

MONEY HANDLING MACHINE

Application filed August 22, 1929. Serial No. 387,695.

My invention relates to new and useful improvements in money handling machines of the well-known "Brandt" type in which a coin tray or magazine is provided for supporting a plurality of stacks of coins adapted to be ejected or discharged by the operation of a key or keys and delivered to suitable position to be received by the operator of the machine or a customer or purchaser or the like.

The principal object of the present invention resides in the provision of novel means whereby the coins ejected or liberated from the machine may be delivered to a point or points at an angle or angles with respect to the machine, either towards the front or rear of the machine, or in the same direction when attached to either end thereof, the delivering means being adapted for attachment to either end of the machine or interchangeable from one end to the other, means being provided in the machine or associated therewith for directing the coins ejected or liberated from the coin tray or magazine towards that end 25 of the machine to which the delivering means is connected.

Another object of the invention consists in so forming the delivery means or mechanism that the coins passing therethrough will travel at a relatively high speed thereby assuring their delivery to the proper point for removal or reception by a person, a relatively shallow cup or receptacle being provided or included in the delivery means for the final 30 reception of the coins prior to their removal by the person, and means being provided to so baffle or retard the movement of the coins as to prevent the possibility of their "jumping" or running over the top of the cup or receptacle due to the speed at which they are traveling.

Still another object of the invention resides in so forming the delivery means or mechanism that the largest denomination of coin 45 will readily pass therethrough for discharge into the cup or receptacle without danger of sticking or clogging.

A further object consists in connecting an inclined spout to the machine for swinging 50 movement or horizontal adjustment relative

thereto and connecting the cup or receptacle to the lower end of the spout for swinging or horizontal adjustment, the two points of adjustment allowing ready manipulation whereby the coins may be delivered at various angles or points relative to the machine.

With the above and other objects in view, which will appear as the description proceeds, my invention consists in the novel details of construction and arrangement of parts described in the following specification and illustrated in the accompanying drawings, and while I have illustrated and described the preferred embodiments of the invention, as they now appear to me, it will be understood that such changes may be made as will fall within the scope of the appended claims.

In the drawings:

Fig. 1 is a longitudinal vertical section through the body of the machine and a portion of the delivery means with parts shown in front elevation and parts of the operating mechanism omitted for the sake of clearness.

Fig. 2 is a diagrammatic view of the delivery means or mechanism with operating parts of the machine omitted for the sake of clearness.

Fig. 3 is an elevation showing one end of the body of the machine with the delivery means connected thereto.

Fig. 4 is a top plan of the construction shown in Fig. 3.

Fig. 5 is a longitudinal vertical section through the delivery means or mechanism.

Fig. 6 is a bottom plan of the delivery means or mechanism, one of the adjustments being shown in dotted line.

Fig. 7 is a detail showing the cup or receptacle detached from the lower end of the spout and the means or bracket whereby the cup is connected to the spout.

Fig. 8 is a transverse vertical section on the line 8—8 of Fig. 4.

Fig. 9 is a section on the line 9—9 of Fig. 3 looking in the direction of the arrows.

Fig. 10 is a section on the line 10—10 of Fig. 3.

Fig. 11 is a perspective showing the plate

100

forming the bottom of the delivery spout; and

Fig. 12 is a section on the line 12—12 of Fig. 3 looking in the direction of the arrows. 5 In illustrating the invention to be protected by the present application and patent resulting therefrom I have omitted, for the sake of clearness, the coin supporting tray and operating mechanism for ejecting the coins it being understood that my delivery mechanism or means may be associated with machines embodying various types or forms of operating mechanism.

15 In the drawings I have illustrated at A the body portion of the machine including the ends 1 and 2 each having an opening 3 therein, the opening 3 not in use being adapted to be covered or closed by a plate 4 detachably connected to the end of the body by means of 20 the screws 5 or other suitable means. Positioned interiorly of the body and detachably connected to the bracket 6, by means of the screw 7 or other suitable fastening is a chute 8 which is downwardly inclined with its upper end resting upon a bar or strip 9 and its lower end projecting through the opening 3 not covered by the plate 4. The chute may be arranged for directing the coins towards either end of the machine and may be positioned as shown either in full lines or dotted lines to deliver the coins through either of the openings 3.

30 I have illustrated and will describe, more in detail, the delivery mechanism or means as being connected to the end 1. At 10 I show a housing or deflector detachably connected to the end 1 by means of the screws 11 or other suitable fastenings, this housing or deflector having an opening 12 in its rear wall or face 35 aligned with the opening 3 and through which the lower end of the chute 8 projects as shown more clearly in Figs. 1 and 5 of the drawings. The lower end of the housing or deflector is flared outwardly to form the depending flange 13 and is slit as shown at 14, more particularly in Fig. 6 of the drawings, for a purpose to be later described and a screw 40 15 operates in a threaded opening intersecting this slit for adjustment thereof. While 45 I have illustrated the top of the housing or deflector as open it will be understood, if desired, the same might be closed.

An open top spout is illustrated at 16 and at its upper end is formed with a ring-like 50 portion 17 adapted to be received within the depending flange 13 of the housing or deflector 10. The ring-like portion is held within the housing or deflector by tightening the screw 15 it being understood that the slit 14 allows for a contracting of the bottom edge of the housing or deflector to tightly engage the ring-like portion. The ring-like portion 17 forms an opening at the top of the spout aligned with the bottom opening of the housing or deflector. The spout is formed

with the removable bottom plate 18 secured in position by means of the screw 19 or other suitable fastening and the bottom or forward end of the plate extends over the forward portion 20 of the spout as shown more particularly in Fig. 5 of the drawings. Depending from the portion 20 is a lug or projection 21 for a purpose to be later described. The forward or lower end of the spout is closed by the end 22 which has its lower portion 23 projecting below the plane of the lower end of the spout bottom for a purpose which will be presently described and the bottom edge of the end is cut away as shown at 24 to provide the depending portion 25 which acts to position and form a bearing for the cup or receptacle to be later described. The formation described provides an opening 26 at the lower end of the spout and through which the coins are adapted to pass. The bottom plate 18 of the spout is of the shape illustrated more particularly in Figs. 5, 9 and 11 of the drawings and the longitudinal sides of the plate are bent upwardly at an angle as shown to provide the portions 27 and the center substantially horizontal portion 28. This shape is of particular advantage in that it is impossible for any coin coming down the spout to lay perfectly flat for the central portion 28 is not of a sufficient width to receive the smallest diameter of coin. In other words if the coins are coming down the spout flat they would not rest upon any one of the surfaces and the central portion of the coin would be supported away from engagement with the spout. This would prevent undue friction.

55 The cup or receptacle for receiving the coins from the spout is shown at 29 and is provided with the depressed portion 30 at the forward or outer end from which the coins may be readily removed with the hand. As shown more particularly in Fig. 5 of the drawings the forward edge of the depressed portion is curved at 31 and terminates into the vertical wall 32. At the rear end the cup or receptacle is provided with the upstanding flange 33 which will engage the depending portion 25 at the bottom of the lower end of the spout as shown. The cup or receptacle is secured to the lower end of the spout by means of the bracket 34 which is secured to the depending portion 21 of the spout by means of the screws 35 or other suitable fastenings. The bracket includes the vertically extending portion secured to the lug or projection 21 and the ring-like horizontal portion 36 provided with the slit 37 where it joins with the vertically extending portion, said slit extending upwardly a distance into the vertically extending portion. A bolt 38 extends through the arms formed by the slit as shown more particularly in Fig. 6 and when this bolt is tightened the ring-like portion will be contracted or reduced to tightly 60 120 125 130

engage the lug or projection 39 depending from the rear end of the cup or receptacle. This lug or projection 39 is received in and extends through the ring-like portion of the bracket and forms a pivot on which the cup or receptacle may be swung relative to the spout when the bolt 38 is loosened. I wish to call particular attention to the fact that the cup or receptacle is relatively shallow and this is of particular advantage to facilitate the removal of the coins discharged therein. As further shown more particularly in Figs. 3 and 5 of the drawings the bottom of the forward end of the cup or receptacle is flat so as to rest upon the counter, table, or other support upon which the machine is positioned and the lug or projection 39 at the rearward end of the cup or receptacle is of such a length that it will normally project beyond the bottom surface of the bracket and also rest upon the surface of the support.

Having fully described the detailed construction I will now bring out more in detail the operation. The coins which are liberated from the coin tray or magazine, by suitable operating mechanism, drop upon the chute 8 and pass down over the chute through the opening 3 and the opening 12 in the back of the housing or deflector 10. They then drop through the bottom opening in the housing or deflector and the opening at the top of the spout 16 and are discharged into the spout to pass therethrough for discharge through the bottom opening 26 into the cup or receptacle 29. As has been described the bottom of the spout is of such a form or configuration that the coins cannot lie flat thereon but instead will be positioned so that a portion of the coin will be supported in spaced relation to the surface to prevent undue friction. The coins will be discharged over the chute 8 at relatively high speed and due to such speed certain of the coins will jump over the opening and engage the forward end or wall of the housing or deflector which acts as a baffle and directs the coins through the bottom opening into the spout. It will be appreciated that in a machine of the character described it is desired, at all times, that the coins be delivered towards the forward end of the cup or receptacle to facilitate removal and also to aid in the removal it is desirable to have the cup relatively shallow so that the fingers of the person may be positioned therein to withdraw the coins. To allow the coins to pass at sufficient speed to accomplish the above purpose the spout is arranged at a relatively high angle and the coins passing through or over the spout will be discharged at a relatively high speed or velocity. In order to prevent the coins thus discharged, from the spout into the cup, from jumping over or rolling over the edges of the cup or receptacle the lower end of the spout is closed

by the wall 22 and the lower portion or edge of the wall projects below the plane of the top surface of the spout. The coins passing from the end of the bottom of the spout will engage the wall 22 which acts as a baffle and the speed of movement is reduced to such an extent that when the coins are delivered into the cup or receptacle there will be no possibility of them jumping or rolling over the edge thereof. If the coins are coming down the spout relatively flat or rolling on edge they will nevertheless engage the wall 22 so that their speed will be reduced. If relatively flat they will drop through the opening 26 into the cup or receptacle without difficulty but in order that any coins rolling on edge may properly pass into the cup the bottom edge of the wall 22 is positioned above the upper surface of the cup or receptacle a sufficient distance to allow a coin of the highest diameter to pass therebeneath even though remaining or rolling on edge. The cup or receptacle is of the formation described so that the coins discharged therein will be directed into the depressed portion 30. When the coins are positioned in the depressed portion 30 the person to remove the same will place his fingers into the depressed portion and draw the coins towards the front end of the cup or receptacle. As he does this the coins are drawn over the curved surface 31 which has a tendency to direct them into the hand to facilitate removal. It will thus be seen that the coins can properly pass over and through the spout for discharge in proper position into the cup. There are two baffles provided for retarding the coins one being the forward wall of the housing or deflector 10 and the other being the end wall 22 at the bottom of the spout. I also claim particular advantage in having the spout mounted for adjustment relative to the body of the machine and the cup or receptacle adjustable with respect to the end of the spout as well as having both the spout and cup with the housing interchangeable to either end of the body of the machine. Machines of the character described are used in a large number or variety of places and for various uses. At times the support upon which the machine is placed is relatively small. As an example I might point to the relatively small booths commonly used at moving picture theatres and in which a ticket and change are delivered to a purchaser through a small opening. At times the machine is positioned at the right of the cashier or operator and at other times to the left. According to the size of the support and for convenience the machine while at either side of the operator may be arranged at different angles. With the machine which I have provided the delivery spout and cup with the supporting housing or deflector may be connected to either end of the machine, as stated, and then the

130

spout and cup may be adjusted to different angles to discharge the coins in the direction desired. When desired the cup and spout may be adjusted so that the cup will be positioned through an opening in a booth or the like as shown more particularly in Fig. 2 of the drawings. No matter on what end of the machine the spout and cup are secured the same may be directed in any direction or angle desired. In other words while attached to either end of the machine they may be directed towards the front of the machine or to the rear of the machine or to any angle relative thereto.

15 It is to be understood that the arrangement of the runway or spout at a relatively high angle or pitch will permit and insure all coins passing down the runway without lodging, which lodging or tendency to lodge is seriously objectionable where such an open runway is, in commercial usage, exposed and receives, to a greater or less extent, a coating of dust or the like.

Further, with the foregoing in mind, it is apparent that the coins may at times pass down the runway or spout at somewhat different speeds, but even under the relatively high speed the swivel connection and baffle are such that while a coin even though riding vertically on edge after contacting the baffle may roll freely beneath the baffle, but its momentum having been reduced, it cannot roll over the edge of the cup. This is true of the greatest as well as the least diameter of coins for which the machine is designed and irrespective of the angular positioning of the cup relative to the inclined spout, the swivel connection and baffle being arranged and correlated to permit the largest coin when rolling to at all times have sufficient room to permit its clearing under the baffle which it has struck, even though the coin should be riding vertically on edge.

45 Insofar as common subject matter appears therein this application is a continuation of my copending applications filed May 24, 1924, Serial No. 715,661 and filed April 9, 1926, Serial No. 100,903.

Having fully described my invention what 50 I claim as new and desire to secure by Letters Patent is:

1. The combination with an inclined coin spout formed at one end for operative association with coin delivery means of a relatively shallow coin receiver adapted to be associated with the other end of the spout, said receiver having an open forward or toe portion accessible to the hand of the user and an elevated heel portion registering at its top with a discharge opening from the spout, the heel and toe portions of the coin receiver being merged at the bottom through an inclined bottom wall, the bottom of the toe portion being formed into a distinct recess for the reception of the coins.

2. The combination with an inclined coin spout formed at one end for operative association with coin delivery means of a relatively shallow coin receiver adapted to be associated with the other end of the spout, 70 said receiver having an open forward or toe portion accessible to the hand of the user and an elevated heel portion registering at its top with a discharge opening from the spout, the heel and toe portions of the coin receiver being merged at the bottom through an inclined bottom wall, and the side walls of the heel portion extending upwardly a substantial distance above the side walls of the toe portion to provide clearance between the bottom of the heel portion and the bottom of the spout for the largest size coin to be dispensed through the machine.

3. The combination with an inclined coin spout formed at one end for operative association with coin delivery means of a relatively shallow coin receiver adapted to be associated with the other end of the spout, 80 said receiver having an open forward or toe portion accessible to the hand of the user and an elevated heel portion registering at its top with a discharge opening from the spout, the heel and toe portions of the coin receiver being merged at the bottom through an inclined bottom wall, and the side walls of the heel portion extending upwardly a substantial distance above the side walls of the toe portion to provide clearance between the bottom of the heel portion and the bottom of the spout for the largest size coin to be dispensed through the machine, the lower wall of the spout adjoining the elevated sides of the heel portion constituting a baffle to retard or upset coins passing from the spout to the coin receiver.

4. The combination with an inclined coin spout formed at one end for operative association with coin delivery means of a relatively shallow coin receiver adapted to be associated with the other end of the spout, 110 said receiver having an open forward or toe portion accessible to the hand of the user and an elevated heel portion registering at its top with a discharge opening from the spout, the heel and toe portions of the coin receiver being merged at the bottom through an inclined bottom wall, and the side walls of the heel portion extending upwardly a substantial distance above the side walls of the toe portion to provide clearance between the bottom of the heel portion and the bottom of the spout for the largest size coin to be dispensed through the machine, the lower wall of the spout adjoining the elevated sides 115 of the heel portion constituting a baffle to retard or upset coins passing from the spout to the coin receiver, said end wall baffle depending below the plane of the inclination of the bottom of the spout to intersect said 120 125 130

plane and constituting an apron or barrier therebelow.

5. The combination with an inclined coin spout formed at one end for operative association with coin delivery means of a relatively shallow coin receiver adapted to be associated with the other end of the spout, said receiver having an open forward or toe portion accessible to the hand of the user
10 and an elevated heel portion registering at its top with a discharge opening from the spout, the heel and toe portions of the coin receiver being merged at the bottom through an inclined bottom wall, the bottom of the
15 toe portion being formed into a distinct recess for the reception of the coins, and the forward portion of the recess being curved to aid in directing the coins into the hand of the user.
- 20 6. The combination with an inclined coin spout formed at one end for operative association with coin delivery means of a relatively shallow coin receiver adapted to be associated with the other end of the spout,
25 said receiver having an open forward or toe portion accessible to the hand of the user and an elevated heel portion registering at its top with a discharge opening from the spout, the heel and toe portions of the coin
30 receiver being merged at the bottom through an inclined bottom wall, and the side walls of the heel portion extending upwardly a substantial distance above the side walls of the toe portion to provide clearance between the
35 bottom of the heel portion and the bottom of the spout for the largest size coin to be dispensed through the machine, said upwardly extending portion of the side walls being of a height approximating one-half the
40 depth of the coin receiver.

In testimony whereof I hereunto affix my signature.

EDWARD J. BRANDT.
